BALLING GUN FOR USE IN INTRODUCING
BOLUSES INTO AN ANIMAL'S MOUTH

James H. Klein, Greenwood Village, and Francis I. Tal-
lentire, Aurora, Colo., assignors to Frost Engineering
Development Corporation, Englewood, Colo., a corpo-
ration of Colorado

Filed June 19, 1963, Ser. No. 75,417

Term of patent 14 years

(Cl. D83—12)

FIG. 1.

FIG. 2.

FIG. 3.

FIG. 4.

FIGURE 1 is a side elevation of a balling gun for use in introducing boluses into an animal's mouth showing our new design;

FIGURE 2 is a bottom plan view;

FIGURE 3 is a rear elevation; and,

FIGURE 4 is a front elevation.

We claim:

The ornamental design for a balling gun for use in introducing boluses into an animal's mouth, as shown.
